(57) **CLAIM**

The ornamental design for a display panel for computer monitor as shown and described.

DESCRIPTION

FIG. 1 is a front, right, top perspective view of a display panel for computer monitor showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion "8" of FIG. 1; and,

FIG. 9 is an enlarged view of portion "9" of FIG. 1.

The dash-dash broken lines depict portions of the display panel for computer monitor that form no part of the claimed design.

The dot-dot-dash broken lines in FIGS. 1, 8 and 9 represent the extents of the enlarged detail views and form no part of the claimed design.

1 Claim, 9 Drawing Sheets
